(57) **CLAIM**

The ornamental design for handle for an electrical ascender as shown and described.

DESCRIPTION

Handle for an electrical ascender

1.1 is a perspective view of a handle for an electrical ascender showing the new design.

1.2 is a back view thereof.

1.3 is a front view thereof.

1.4 is a top view thereof.

1.5 is a bottom view thereof.

1.6 is a left view thereof.

1.7 is a right view thereof.

1 Claim, 7 Drawing Sheets(56)
